(57) **CLAIM**

The ornamental design for a dispenser, as shown and described.

DESCRIPTION

In a preferred embodiment, the nature of this product is as a dispenser for liquids, such as soaps and lotions, especially those used at kitchen and bathroom sinks.

FIG. 1 is a left, top, front perspective view of a dispenser embodying my new design;

FIG. 2 is a left side elevational view thereof, the right side elevational view being a mirror image of the left side shown;

FIG. 3 is a front elevational view thereof;

FIG. 4 is a rear elevational view thereof;

FIG. 5 is a top plan view thereof; and,

FIG. 6 is a bottom plan view thereof.

The broken line representation of a wall structure in FIG. 6 is for the purpose of illustration only, and form no part of the claimed design.
